LAUNDRY DRIER

Charles J. Holub, Columbus, Ohio, assignor to
W. E. Lamneck Company, Columbus, Ohio, a
corporation of Ohio

Application April 29, 1931. Serial No. 533,762

1 Claim. (Cl. 34—19)

This invention relates to improvements in laundry driers, particularly for home service, made of sheet and of knock-down construction so that the parts can be compacted for marketing and shipping and adapted to be interfitted or slipped together for simple and convenient assembly and erection, at the place for use, into a sturdy structure.

The structure provides a compact heating unit, constituting a heater of elongated tubular radiator form for approximately the base area of the cabinet, enclosed or jacketed by a casing as the base for the cabinet, with the casing of the heating unit separable from the cabinet, enabling the cabinet to be made of knock-down construction. The cabinet provides an ample size drier compartment within which the laundry or wet clothing is suspended upon removable racks or bars, and the heater for circulating a constant supply of fresh heated air from the base of the cabinet, upwardly, through and about the wet clothing, escaping and carrying off the moisture from the clothing, out, through openings in the top of the cabinet. A gas burner or heating element is disposed within a manifold head of the tubular radiator of the heater, under thermostatic control for automatically regulating and maintaining a definite drying temperature within the cabinet.

The present invention involves the use of a heater preferably of elongated form, and consisting of a plurality of sheet metal tubes extending horizontal at a slight inclination, arranged in superposed sets with the opposite ends of the tubes connected, in unit, to manifolds or box-form heads, with a gas burner or heating element in one of the manifolds and the other manifold provided for connection with a vent flue. A heater enclosed or jacketed by a sheet metal, rectangular casing, as a removable or separable base for the drier cabinet, with the parts of the heater securely joined together and permanently mounted within the casing, preventing any leakage of gases or fumes from the heater into the drier cabinet which has its lower portion open to the heater. The heater with its casing, as a unit complete ready for service when the gas burner or heating element supply connections are coupled to a supply line.

An object of the invention is to provide a laundry drier cabinet, preferably of knock-down construction, with a rigid shallow box-form of base occupied by a heater and the base as a heating unit detachable from the cabinet.

Another object of the invention is to provide

a heating unit as a base for a laundry drier cabinet, constituting a heater enclosed and jacketed by a rectangular sheet metal casing, the upper edges of the casing formed for making a slip joint connection with the walls of the cabinet, to detachably mount the cabinet upon the heating unit.

Another object of the invention is to provide a casing for a base heating unit of a laundry drier cabinet with a recessed end wall for sustaining and housing the fittings and appliances for a gas burner or heating element within the body line of the structure.

Other features and advantages relate to improvements in details of construction, all of which will be more fully set forth in the description of the accompanying drawings, forming a part hereof, in which:

Figure 1 is a perspective view of the improved laundry drier, with a portion at the lower end broken away to disclose the face plate of the fire box.

Figure 2 is an enlarged sectional view of the end wall portion of the heating unit as the base of the drier cabinet and the joint connecting the base with a wall of the cabinet thereabove.

Figure 3 is an enlarged horizontal section through a corner of the cabinet.

Figure 4 is an enlarged horizontal section through a joint strip under and connecting sheet sections of the rear wall of the cabinet.

Figure 5 is an enlarged vertical section through a corner of the lower portion of the cabinet to illustrate the means for adjusting the legs.

Figure 6 is a front elevation of the cabinet with the front doors removed and with the base heating unit in section.

Figure 7 is a top plan view of the heating unit or base, with a portion broken away to illustrate the burner within a combustion chamber or box at one end of the unit.

Figure 8 is a section on line 8—8, Figure 6, of the cabinet.

Figure 9 is a section on line 9—9, Figure 6, of the heating unit.

Figure 10 is a section on line 10—10, Figure 5.

Figure 11 is a cross section of a modified form of cabinet corner post.

The structure of the cabinet providing the drier compartment corresponds to the construction of laundry drier illustrated and described in Letters Patent No. 1,550,700, to C. J. Holub, August 25, 1925, particularly as to its knock-down characteristics, corner post construction

and method of detachably joining the sheet metal walls to the posts.

The present embodiment provides a base heating unit separable from the cabinet with the heater and its parts rigidly and securely mounted within the casing of the base unit, instead of knock-down as featured in said patent, although in general principle is similar.

The upper unit or cabinet which provides the 10 drying compartment for the clothes preferably comprises sheet metal end walls 1, 2 and rear wall 3 as substantially plane sheets engaged or slipped into grooves or channels formed in the corner posts 4, each post being made of a sheet 15 metal blank bent into angle bar shape. The limbs of the bar, at their outer longitudinal ends, are reversely bent upon themselves, each to provide a channel 5, with the channel opening outwardly and forming a slip joint to receive 20 the marginal edge of a wall or metal sheet. The double lap bend for the edges of the limbs of the joints adds rigidity to the post structure, aside from providing slip joints for removably joining the walls to the posts under sufficient 25 frictional contact to effect a proper seal and to accommodate for contraction and expansion of the metal of the walls to avoid warping or buckling of the sheets. With the edges of the 30 sheets forming the walls of the cabinet merely socketed into the channels of the posts, no bending or machining of the sheets is required for jointing, reducing the cost of manufacture, avoids injury to the galvanizing coating of the metal and facilitates in assembling or disassembling the parts.

Owing to the width of the cabinet, the rear wall 3, is made up of several panels or sheets and the panels joined together by a channel bar 6, comprising, a sheet metal blank bent upon itself 40 into T-form, to provide a central reinforcing rib 7, longitudinally of the bar and a pair of oppositely disposed and aligned limbs 8-8 each formed with a longitudinal channel into which the opposing ends of two sheets or panels are 45 respectively slipped, forming a joint similar to that of the posts.

The front of the cabinet is furnished with a pair of doors affording an opening for the full width and height of the cabinet. A top wall 50 section 9 for the front of the cabinet above the doors, has its opposite longitudinal ends engaged with the front corner posts and its lower longitudinal margin is offset inwardly, giving rigidity to the wall and provides a stop for the doors.

55 The upper ends of the walls of the cabinet are bent to receive and secure a cover or top 10 of tray or box-form, apertured along its lower margins to provide vent openings. The tray or box construction of the top makes it very rigid 60 and when connected with walls holds the cabinet square. The interior of the cabinet is provided with suitable racks removably supporting rods upon which the clothes are sustained for drying.

65 The lower end of the walls of the cabinet extend slightly below the lower ends of the corner posts for making a slip-joint connection with the upper edge of the walls of the heater casing 11. The joint or connection being substantially as 70 for the walls with the corner posts.

The casing 11 of the heater unit is of double wall structure for the front, rear and one of the end walls, each consisting of an outer wall 12 having an inturned flange 13 along its lower longitudinal edge to which a base plate and in-

ner wall are riveted. The upper longitudinal edge of the outer wall 12 is bent upon itself with several reverse bends forming a pair of channels 14, 15 and an inturned double ply lateral flange 16 at the base of the reverse bends serving as a ledge for a screen tray 17 as a bottom for the cabinet to guard against any of the clothing which may fall from the racks or dropped, from coming in direct contact with the heater or highly heated surfaces and thereby scorched or burned.

The channel 15 formed by the crimping of the upper longitudinal margin of the outer wall forms a socket for frictionally engaging the lower protruding edge of a wall of the cabinet 80 for removably connecting the cabinet with the heater casing, and the second channel 14, of a seam for joining the upper angle flanged end 19 of the inner wall 18. (See Figure 2.) The inner wall 18 along its lower longitudinal margin is bent to form a lateral flange 20 registering with the inturned flange 13 of the outer wall and riveted thereto with the base plate 21 for the heater casing intermediate thereof. Flanging the opposite longitudinal margins of the 100 inner wall reinforces the same and provides for definitely spacing the inner and outer walls.

The ends of the double wall sides of the heater casing are mitered and connected at each corner by an angle bar 22 bearing against 105 the inside surface of adjoining outer walls. Each corner of the heater casing has an angle bar 23 at the outside thereof and of a length to protrude beyond both upper and lower ends of the casing with the lower projecting portion 110 of the angle or corner bar 23 serving as a leg and the upper projecting end of the bar for connecting the cabinet to the heater casing. The parts are connected by bolts 24 with provision made for vertically adjusting the outer 115 angle bar 23 for varying its leg height. The corners are reinforced providing a very sturdy structure.

One end of the heater casing has a single wall 120 bent to recess the same within the casing and at its outer side carries a cast metal face plate 26 having an inwardly extending snout 27 leading into the fire box, or burner chamber, of the heater, and a door 28 therefor. The end wall 25 about the face plate is perforated furnishing 125 air intake openings for the interior of the heater casing and cabinet.

The heater in principle is similar to that disclosed in the aforesaid patent although not of knock-down type, the parts being preferably 130 rigidly connected to more effectively prevent the escape of gas or fumes into the heater chamber and cabinet. The heater is permanently mounted within the heater casing and as a unit as separable or detachable from the cabinet.

The heater comprises a plurality of radiator tubes 28 arranged in superposed sets, all relatively spaced from one another and longitudinally inclined upwardly from their forward ends, with their opposite ends respectively connecting with sheet metal rectangular or box-form manifold casings 29, 30. The manifold 29 for the forward end of the radiator tubes provides a burner or combustion chamber for the heater with its front wall spaced slightly from the front wall 25 of the heat casing, and its base wall spaced or elevated from the base plate 21 of the heat casing.

A gas burner 31 is mounted within the lower portion of the front manifold 29 having its in-

- take or mixing tube 32 extending horizontally forward therefrom and through the front wall of the manifold, casing wall 25 and face plate 26 connecting with the gas supply piping 33 in front of the face plate. The gas piping 33 has connections interposed therein for a pilot burner and thermostat valve 34, the valve 34 having its thermal tube extending into the heater casing immediately above the heater manifold 29. 5
- 10 The interior of the heater manifold 29 is provided with a pair of horizontal superposed baffles 35, 35, the upper thereof overreaching the lower, and the lower provides a partition between the inlet ends of the upper and lower sets 15 of radiator tubes. The heat from the rear portion of the gas burner is diverted into the lower set of radiator tubes, while the heat from the forward portion of the burner is directed into the upper set of radiator tubes. 20
- 20 A pair of heat deflector or baffle plates 36, 36, recessed within the top of the heater casing, one extending over the forward end of the heater, the second over the rear portion of the heater, protect the highly heated portions of the 25 heater from being directly exposed to the lower portion of the interior of the cabinet, and intermediately provide an opening leading into the cabinet. The heated air from the chamber about the heater is directed into the center of 30 the cabinet for effecting a more even distribution of temperature through the entire cabinet. The air is admitted into the heating chamber through an opening in the bottom 21 at the left end below the manifold 30. 35
- 35 The walls of the rear manifold 30 connect with the outer wall of the double walled end of the heater casing, and the manifold connects with a vent flue pipe 37 extending vertically with the cabinet for connection with a chimney flue of 40 a building.
- 40 The thermostat valve 34 is of commercial type and serves for an automatic gas control for the gas burner and regulation of the drying temperature within the cabinet and can be set for 45 maintaining a definite temperature within the cabinet.
- 45 Recessing the end wall, 25 of the heater casing and mounting the pipe fixtures for the burner on the front face thereof brings the 50 same within the outside body line of the heater casing and cabinet, amply housed and securely
- connected ready for coupling to a gas supply line, of great advantage in a household appliance as it facilitates and simplifies its installation. 55
- Air, for circulation through the cabinet is also admitted through the perforations in the recessed end wall 25 of the heater casing. The air admitted into the heating chamber thus passes over and about the heat radiating surfaces of the heater, and thence upwardly 80 through the central opening formed by the baffles 36, 36 into the cabinet and escaping through the perforations in the top. Thereby a constant supply of fresh, heated dry air is furnished from below the cabinet and circulated 85 upwardly about and through the wet clothing suspended within the cabinet, absorbing the moisture and escaping out through the top of the cabinet, presenting a most favorable condition 90 for quickly drying the clothing. 95
- In Figure 11 a modified form of corner post is illustrated and primarily employed for the two front posts to which the doors are secured. The general construction of the post is the same as heretofore described, constituting a strip of 100 sheet metal bent into angle bar shape with the longitudinal ends or outer margins of the limbs each reversely bent upon itself in a double lap providing a pair of adjacent channels, one as the outer for the reception of the marginal edge 105 of a panel sheet or the like, and the second or inner, for the reception of the marginal edge of a sheet metal strip 38, the strip 38 is of a form to provide a cross brace for the limbs of the posts or bar with the ends of the strip respectively socketed into the laps at the ends of the limbs, the brace stiffens the limbs so that they cannot be flexed under the weight of the doors. 110
- Having described my invention, I claim:— 115
- A laundry drier, comprising, a sheet metal cabinet, a heating unit for the base of the cabinet providing a sheet metal casing secured to the cabinet, a heater mounted within the casing and jacketed thereby, the casing having a recessed end wall for housing and supporting the fittings and appliances for a heating element of the heater within the confines of the heater casing. 120
